UNITED STATES PATENT OFFICE.

LESTER H. SPARKS, OF LAKEWOOD, NEW JERSEY, ASSIGNOR OF FORTY-NINE ONE-HUNDREDTHS TO JENNIE I. MILLER, OF LAKEWOOD, NEW JERSEY.

GASOLENE CUT-OUT.

1,249,846.

Specification of Letters Patent.

Patented Dec. 11, 1917.

Application filed March 4, 1914, Serial No. 822,358. Renewed July 18, 1917. Serial No. 181,453.

To all whom it may concern:

Be it known that I, LESTER H. SPARKS, a citizen of the United States, residing at Lakewood, in the county of Ocean, State of New Jersey, have invented certain new and useful Improvements in Gasolene Cut-Outs; and I do hereby declare the following to be a full, clear, and exact description of the invention, such as will enable others skilled in the art to which it appertains to make and use the same.

This invention relates to means for controlling the operation of gas engines through the cutting out of the supply of combustible 15 to such engine.

The principal object of the invention is to provide an improved valve arrangement which is electrically operated and may be used in connection with a timer such as is 20 described in my copending application No. 764,632, filed April 21, 1913.

A second object of the invention is to provide a locking means which will prevent the accidental closing off or opening up of the 25 valve through jar or shock.

With the above and other objects in view the invention consists in general of certain novel details of construction and combination of parts hereinafter fully described, 30 illustrated in the accompanying drawings and specifically claimed.

In the accompanying drawings, like characters of reference indicate like parts in the several views, and:

35 Fig. 1 is a general side elevation of a portion of the operating mechanism of a gas or gasoline engine showing the location of the improved device.

Fig. 2 is a section on the line 2—2 of 40 Fig. 1.

Fig. 3 is a section on the line 3—3 of Fig. 2.

Fig. 4 is a detail section on the line 4—4 of Fig. 2.

45 In carrying out the objects of this invention there is provided a lower casing 10 which may be termed the valve casing and this lower casing has at each side a glass or other transparent window 11 so that the 50 location of the column of fluid therein may be observed. Within this lower casing is the valve mechanism proper. The top of this lower casing is formed by the bottom of an upper casing 12 which contains the 55 electro-magnetic coils for operating the de-

vice. Extending from the lower casing to a gas tank 13 is a tube 14 which opens into the lower casing at the upper part of one side thereof. Extending from the lower part of the opposite side of said lower casing is a tube 15 which leads to the carburetor 16. Mounted in the upper casing 12 is a plurality of electro-magnets 17 arranged so as to form two pairs. The inner ends of the windings of these magnets are all connected to the respective cores 18 and on top of these magnets is mounted a bracket 19 wherein is pivoted a shaft 20 having arms 21 extending outward therefrom and engaging said cores 18, the latter being cut 60 away at their upper ends to form curved contact surfaces 21 wherewith said arms 65 constantly engage.

Within the upper casing is also a plate 75 of insulating material 22 and on this plate of insulating material are mounted the binding posts 23, 24 and 25. The last two binding posts are connected to suitable contact plates 26 on the plate 22. Depending from the shaft 20 is an arm 27 which carries the 80 contact fingers 28. This arm 27 is of insulating material so that the contact fingers are insulated from the shaft 20. The contact fingers are connected by means of a wire 29 with the binding post 23 while the respective plates 26 are connected to the 85 respective posts 24 and 25. At 30 is a battery which is connected by a wire 31 with the contact post 23 and by a wire 32 with a switch 33 which is to be operated by the 90 timer above mentioned. This switch operates over two contacts 34 which are connected by wires 35 with the respective posts 24 and 25. A normally open bell circuit 36 may be used to connect the wires 32 and 35 95 as a testing circuit.

The casing 10 is provided with suitable openings wherein are located the valve seats 37 with which the respective pipes 14 and 15 are connected. Extending transversely of 100 said casing 10 is a shaft 38 supported on brackets 39 which are connected to the lower ends 40 of the cores 21, said lower ends projecting well down into the casing. Swinging from the brackets 39 are two bell crank 105 levers 41 and these levers support armatures 42 which lie inside of the respective pairs of core ends 40. The outer arms are provided with rabbets 43 to form latches. On the shaft 38 is pivoted a lever 44 which has 110

a companion lever at the opposite end of the shaft and these two levers 44 support the armatures 45 which lie beneath the respective pairs of core ends 40. Mounted on the shaft 38 and rotating therewith is a lever 46 which carries the valve stems 50 the latter being loosely mounted on the lever and held in position yieldingly by means of springs 51. These valve stems carry the valves 52 which are arranged to seat in the respective seats 37.

In the operation of the device when the switch 33 is thrown into one position current will flow through the binding post 24 and contact finger 28, passing on its way through the right hand magnet of Fig. 3. The first action will then be to attract the right hand armature 42 which will release the armature 45 and permit this to be attracted by the poles 40. This will serve to rock the lever 46 so as to close the valves. At the same time the upper ends of the magnet cores will draw down the right hand ends of the armature levers 21 thus causing the contact fingers to move over to the contact 26 and break the circuit between the right hand magnets and the battery. This circuit will remain broken until the switch 33 is moved to the other contact 34 whereupon the reverse of the above operation will take place, the left hand armature 45 being unlatched and drawn up and the parts caused to assume the position shown in Fig. 3, thus opening the valves.

35 There has thus been provided a simple and efficient device of the kind described and of the character specified.

Having thus described the invention, what is claimed as new is:—

40 1. In combination, a valve, a casing, a

pair of magnets mounted in said casing, a pivoted arm engaging the cores of said magnets, a depending arm engaging said pivoted arm, contact fingers at the extremity of said depending arm, a pair of contact plates 45 adjacent to said fingers, a pair of levers mounted adjacent to each other and to the lower ends of the respective cores of said magnets, armatures supported on said levers, brackets connected to the lower ends 50 of said cores, a shaft mounted in said brackets midway between said levers, a lever mounted on said shaft, armatures at the respective ends thereof controlled respectively by said first mentioned levers, and an actuating lever pivoted on said shaft and disposed transversely of said last mentioned lever and movable therewith, a plurality of valves, said actuating lever operably connected to said valves and adapted to open 60 and close said valves alternately when said contact fingers are moved from one contact plate to the other.

2. In a gasoline cut out device, a gasoline chamber, and pipes communicating with 65 said chamber, a lever pivotally mounted in said chamber, a cross arm connected to said lever, valves on the respective ends of said cross arm adapted to close said pipes, the said cross arm being slidably connected to 70 said valves, springs interposed between the valve heads and the cross arm and means for rocking said lever.

In testimony whereof, I affix my signature, in the presence of two witnesses.

LESTER H. SPARKS.
